Primary Examiner — Kevin K Rudzinski(74) **Attorney, Agent, or Firm** — Shook, Hardy and Bacon L.L.P.(57) **CLAIM**

The ornamental design for a garment, as shown and described.

DESCRIPTION

FIG. 1 is a front view of a garment showing my new design; FIG. 2 is a rear view thereof; FIG. 3 is a first side view thereof; FIG. 4 is a second side view thereof; and, FIG. 5 is a front, perspective view thereof.

The long-and-short broken lines form an unclaimed boundary around at least a portion of the claimed subject matter, and form no part of the claim. The even-length broken lines, which show the remainder of the article, are directed to environment, represent unclaimed subject matter, and form no part of the claimed design.

The contrast in shading represents a contrast in appearance only and does not represent any particular color, material, texture or finish.
